(57) **CLAIM**

The ornamental design for a scalloped squirrel baffle, as shown and described.

DESCRIPTION

FIG. 1 is a perspective view of a scalloped squirrel baffle showing my new design;

FIG. 2 is a top plan view thereof;

FIG. 3 is a bottom plan view thereof;

FIG. 4 is a front elevational view thereof;

FIG. 5 is a right side elevational view thereof;

FIG. 6 is a perspective view of a second embodiment of a scalloped squirrel baffle showing my new design;

FIG. 7 is a top plan view thereof;

FIG. 8 is a bottom plan view thereof;

FIG. 9 is a front elevational view thereof; and,

FIG. 10 is a right side elevational view thereof.

The broken lines shown in FIGS. 1 and 6 are for illustrative purposes only and form no part of the claimed design.
